(57) CLAIM

The ornamental design for a portable garden planter, as shown and described.

DESCRIPTION

FIG. 1 is a perspective view of a portable garden planter, showing my new design.

FIG. 2 is a front elevation view thereof, the rear elevation view being identical thereto;

FIG. 3 is a left side elevation view thereof, the right side elevation view being identical thereto; and,

FIG. 4 is a top plan view thereof.

The broken lines shown in FIGS. 1 and 4 depict environmental subject matter only and form no part of the claimed design.
